United States Patent Office.

MONROE B. WASHBURN, OF BROOKLYN, NEW YORK.

Design No. 3,466, dated April 27, 1869.

DESIGN FOR A VENTILATOR-DOOR.

The Schedule referred to in these Letters Patent and making part of the same.

I, MONROE B. WASHBURN, of the city of Brooklyn, in the county of Kings, and State of New York, have invented a new Design for Ventilator-Doors for Rail-way-Cars, and other purposes; and I do hereby declare that the following is a full, clear, and exact description of the same, reference being had to the accompanying photograph, which forms a part of this specification.

In this design for ventilator-doors, A is a door proper, of rectangular form, and upon which is represented, in *bas-relief*, a cherub, B, shielding himself from the wind. C is the door-frame, surrounding the door, and upon

which are represented, in *bas-relief*, cherubim B' B', who occupy positions on each side of the door, blowing the wind into or toward the door.

What I here claim, and desire to have secured by Letters Patent, is—

The design for ventilator - doors, substantially as herein described.

M. B. WASHBURN.
